RACK FOR SPORTING EQUIPMENT

John L. Kroll, New London, Conn., assignor to Jayfro Athletic Supply Co., Inc., New London, Conn.

Filed May 17, 1963, Ser. No. 74,941

Term of patent 14 years

(Cl. D80—9)

Fig.1.

Fig. 2.

Fig. 3.

FIG. 1 is an end elevational view of a rack for sporting equipment embodying my new design;

FIG. 2 is a side elevational view thereof; and

FIG. 3 is a top plan view of the rack.

I claim:

The new and ornamental design for a rack for sporting equipment, substantially as shown.
